INVENTOR.

UNITED STATES PATENT OFFICE.

DANIEL BROWN, OF CRANSTON, RHODE ISLAND.

SHOT-SPREADER.

SPECIFICATION forming part of Letters Patent No. 899,487, dated May 6, 1902.

Application filed February 15, 1902, Serial No. 94,275. (No model.)

To all whom it may concern:

Be it known that I, DANIEL BROWN, a citizen of the United States, residing at Cranston, in the county of Providence and State of Rhode Island, have invented certain new and useful Improvements in Shot-Spreaders, of which the following is a specification, reference being had therein to the accompanying drawings.

10 Like letters indicate like parts.

Figure 1 is a central longitudinal section of a cartridge having my improved shot-spreader therein. Fig. 2 is a view, partly in elevation and partly in section, as seen on line *x-x* of Fig. 1. Fig. 3 is a central longitudinal section of a cartridge with my improved shot-spreader therein as seen before the shot and outer wad are inserted. Fig. 4 is a side elevation of my invention. Fig. 5 is an end elevation thereof.

My invention is a device to be used in a cartridge for the spreading of shot in firing; and it consists of the novel construction and combination of the several parts, as hereinafter particularly described, and specifically set forth in the claims.

In the drawings, A is the metallic shell of a cartridge, having one end open and the opposite end closed, except at the center, where 30 it is made with a circular flanged aperture in which the cap or primer B is seated.

C is the paper or pasteboard shell, circumferentially shouldered, as shown at *a*, and having one end open and the opposite end thickened and provided with a concave surface, the last-named end being centrally perforated for the reception of the cap or primer B. The metallic shell A fits upon the closed end of the paper or pasteboard shell C, and the 40 open end of the former abuts the shoulder *a* of the latter.

D is the charge of powder in the cartridge, and the same is held in place by the wad E, made of felt or other suitable material.

45 The shot-spreader F, which constitutes my invention, consists of a plate of suitable material, preferably pasteboard, cut in the shape of a rhomboid and mounted within a spring G, made of tempered wire of proper diameter or gage, coiled spirally with the four-sided bends illustrated in Figs. 4 and 5. This shot-spreader and its spring are inserted in

the cartridge, as shown in Fig. 3. It is seen in said figure that only the extreme inner corner *c* of the spreader F (which has the 55 shape of an acute angle) is in contact with the wad E. The shot H fills the space around the shot-spreader F G in front of the wad E. A wad I, preferably of pasteboard, inserted in the shell C, is held in position by the turned 60 or crimped end of the shell C, as illustrated in Fig. 1. When the charge is fired, the wad I is blown out and the turned or crimped end of the shell is opened out straight and the wad E, shot H, and the shot-spreader F G are 65 discharged. The short curved bends *b* of the spring G lie in the shell C in contact with the inner surface of said shell, and therefore when the charge is blown out from the shell (as these points of contact are spirally arranged) 70 a rotary motion is given to the spreader F, and the spreader F in the rotation imparted to it by the movement of the wire G strikes against the shot H and causes them to scatter in angular directions as soon as they are dis- 75 charged from the shell C.

The acute-angled corners *c* of the spreader F are the only portions of it which are in contact with the wads, and these corners are diagonally opposite. This facilitates the 80 rotary movement of the spreader F. If the spreader F at its ends were cut squarely off instead of obliquely, as shown, said ends would be in contact throughout their entire extent with the wads E or I, respectively, 85 which would impede by their friction such rotary movement. So, too, the forward movement of the shot H in the discharge causes some of them to strike against the coils of the wire G, and as the pressure thus exerted 90 is at an angle to said wire this conduces to the desired rotary movement of the spreader. The wire G also has the function of giving weight to the spreader F, and this is a balanced weight, as the wire is regularly disposed upon the spreader from end to end, and as the wire 95 is resilient it has an elastic hold upon the edge of the spreader at certain uniformly-distant points of contact therewith, and being of a comparatively small diameter or gage it does not bend or warp the spreader out of shape, but allows it to retain its surfaces in true planes. The rhomboid shape of the spreader gives a somewhat greater marginal

distance from each outer coil of the wire to the adjacent end of the spreader than would be possible if the ends were square instead of oblique, and this tends to prevent the slipping of the wire from off the spreader in action.

I claim as a novel and useful invention and desire to secure by Letters Patent—

1. The improved shot-spreader herein described, consisting of a rhomboid-shaped piece of pasteboard and a spirally-bent wire in frictional contact with the two long sides thereof, substantially as shown.

2. The combination of the shot-spreader F, made in the shape of a rhomboid, and a wire spirally bent with short curves *b* and intermediate straight portions, said wire being in frictional engagement with the two long edges of the spreader F, substantially as described.

3. In combination with a loaded cartridge-shell having a wad to confine the powder and a wad to confine the shot, a shot-spreader surrounded by said shot and having a rhomboid shape, one acute corner of which is in contact with the first-named wad and the other acute corner of which is in contact with the second-named wad, and a spirally-bent wire in frictional engagement with the two long edges of said spreader and in contact with the interior surface of said shell, substantially as specified.

In testimony whereof I affix my signature in presence of two witnesses.

DANIEL BROWN.
